DESIGN FOR AN AMBULATORY TOY DUCK

Calvin H. Markwood, Denver, Colo.

Application March 27, 1945, Serial No. 118,736

Term of patent 3½ years

(Cl. D34—2)

To all whom it may concern:

Be it known that I, Calvin H. Markwood, a citizen of the United States, residing at the city and county of Denver, State of Colorado, have invented a new, original, and ornamental Design for an Ambulatory Toy Duck, of which the following is a specification, reference being had to the accompanying drawing, forming part thereof.

The figure is a perspective view of an ambulatory toy duck, showing my new design; both sides of the article being substantially the same.

I claim:

The ornamental design for an ambulatory toy duck, as shown and described.

CALVIN H. MARKWOOD.
